DRIER

Rutcher Skagerberg, St. Paul, Minn., assignor to
The Brown Instrument Company, Philadelphia,
Pa., a corporation of Pennsylvania

Application March 12, 1936, Serial No. 63,342

10 Claims. (Cl. 34—48)

This invention relates to drying machines in general and more particularly to those types of drying machines commonly known as continuous driers such as are used in paper mills, textile mills, etc.

It is common in the art to provide continuous driers in paper mills with hollow rolls over which the paper web is fed to be dried. These rolls are heated to cause the drying action, the heating medium usually employed being steam. It is desirable in the process of paper making that the paper be dried to within close limits of a predetermined moisture content. There is a tendency for the paper web to vary in moisture content when it comes off the drier. These variations may be caused by variations in the room atmospheric condition, the thickness of the paper web entering the drier, the operation of the presses and the condition of the press felts which precede the drier, and the nature of the stock used in making the paper web.

It has been the practice in the past to attempt to control the moisture content of the finished paper by controlling the steam applied to the steam drier rolls. Various methods of controlling this steam have been employed, some of which are maintaining constant pressures or temperatures in the steam drier rolls, which pressures or temperatures are adjusted by the operator or which pressures and temperatures are controlled by suitable detectors responsive to the moisture content of the paper web as it leaves the drier. These control systems have their shortcomings due to their particular principles of operation. In these systems it is difficult to maintain accurate control of the moisture content since the steam drier rolls must be constructed of a considerable thickness to withstand centrifugal force and steam pressure, and this thickness retards the transmission of heat to the paper web. Therefore, when a detector or controller calls for increasing or reducing the drying effect there is a considerable lag or loss of time before the action of the steam is felt again at the detector or controller. This type of control system, therefore, involving simply the control of the steam valve supplying steam to the steam drier rolls is unable to control the moisture content of the paper web within very close limits.

It has also been the practice in the past to employ hot air as an auxiliary means of drying paper. The use of this hot air provides additional drying capacity over and above that which is provided by the steam drier rolls. However,

no accurate control of the hot air for drying purposes has been provided.

I find that by varying the volume or temperature or both of the air thus applied to paper driers, there is an instantaneous response. In other words, if the volume or temperature is reduced the drying effect is immediately reduced and the paper becomes damp. If the volume or temperature is increased the paper immediately becomes more dry.

It is therefore the prime object of this invention to provide an automatic control system for a drier wherein the majority of the drying action is obtained by the steam drier rolls, wherein the smaller portion of the drying action is obtained by the hot air drying means, wherein the drying effect of the steam drier rolls is maintained substantially constant and wherein the drying effect of the hot air means is varied in accordance with variations in the moisture content of the paper web as it leaves the drier rolls.

It is another object of this invention to provide a drier utilizing steam rolls and air blasts for drying a substance that is fed over the steam rolls, wherein the heat content of the steam in the steam rolls is maintained substantially constant for a given setting and wherein the drying effect of the air is varied in response to the moisture content of the substance being dried, whereby the substance is dried to a predetermined degree regardless of its condition as it enters the drier.

A further object of this invention is to provide a drier embodying steam roll means over which the substance to be dried is fed, the heat content of which and consequently the drying action of which is maintained substantially constant.

A further object of this invention is to provide a drier in which an air blast is directed at or near the surface of the substance to be dried, the drying effect of the air blast being varied according to variations in the moisture content of the substance to be dried.

Other objects and advantages will become apparent to those skilled in the art upon reference to the accompanying specification, claims and drawings, in which drawings:

Figure 1 is a diagrammatic illustration of my invention as applied to a Yankee drier;

Figure 2 is a diagrammatic showing of a Four-drinier drier with my invention applied thereto;

Figure 3 is a sectional view taken substantially on line 3—3 of Figure 2.

Referring now to Figure 1, 10 designates the paper web coming from conventional press rolls

11 and 12 of the forming end of a paper machine. The web 10 passes over an idler roll 13 and then over the steam drier roll 14 of the Yankee drier. From there it passes over idler rolls 15, 16, 17 and 18 to a calendar stack, not shown.

5 Heating fluid which may take the form of steam is supplied through a pipe 20 under the control of a valve 21 to the drier rolls 14 to heat the roll 14 and thereby accomplishing a drying 10 action on the paper web 10. The valve 21 may be operated by a proportioning motor 22 which may be of the type shown and described in Patent 1,989,972, issued to Louis L. Cunningham on February 5, 1935. Condensed steam may be drawn 15 from the drier roll 14 by means of a pipe 23.

Power may be supplied to the proportioning motor 22 by means of line wires 25 and 26 leading from some source of power not shown. The proportioning motor 22 may be positioned in any 20 number of a plurality of positions by means of a controller, generally designated at 27. This controller 27 may comprise a bellows 28 for operating a slider 29 with respect to a potentiometer coil 30, the potentiometer coil 30 being connected 25 by wires 31 and 32 and the slider 29 being connected by a wire 33 to the proportioning motor 22. If it be desired to operate the controller 27 in accordance with temperatures in the drier roll 14, the bellows 28 may be connected by a suitable 30 capillary 35 to a bulb, not shown, containing a volatile fill and located in the drier roll 14. The arrangement is such that as the steam pressure or temperature increases, the slider 29 is moved upwardly with respect to the potentiometer coil 35 to operate the proportioning motor 22 to position the valve 21 towards a closed position. Likewise, a decrease in steam pressure or temperature causes movement of the slider 29 downwardly with respect to the potentiometer coil 30 to operate 40 proportioning motor 22 to move valve 21 towards an open position. In this manner the valve 21 is positioned in accordance with steam pressures or steam temperatures to maintain the heat content of the drier roll 14 substantially 45 constant and, therefore, the drying effect of the drier roll 14 is maintained substantially constant. While I have illustrated in this embodiment of the invention the potentiometer slider 29 as being actuated by a temperature responsive device it 50 is to be understood that this slider may be actuated by changes in pressure of the steam if so desired.

In order to cause drying of the paper web 10 by means of an air blast, I provide on a Yankee 55 drier a hood 37 over the drier roll 14, the hood 37 receiving a supply of heated air from a fan 38 which may be driven by any suitable means, such as a pulley 39. Fan 38 receives air from a radiator or heat exchanger 40. Heating fluid, which 60 may take the form of steam, may be supplied to the radiator 40 by means of pipes 41. The hood 37 is provided with openings or tuyères 42 for causing the air forced into the hood 37 to impinge upon the surface of the paper web 10 and 65 thereby cause a further drying action on the paper web 10. Moisture laden air is drawn off the paper web 10 through a passage 43 by means of a fan 44 which may be driven by any suitable means, such as a pulley 45.

70 The supply of steam to the heat exchanger or radiator 40 may be controlled by a valve 46 which in turn may be positioned in any number of positions by a proportioning motor 47, which may also take the form shown and described in the 75 above referred to Cunningham patent. Power

is supplied to the proportioning motor 47 by means of line wires 48 and 49 leading from some source of power, not shown. The proportioning motor 47 may be connected by wires 50 and 51 to a potentiometer coil 52 and by a wire 53 to a slider 54 cooperating with the potentiometer coil 52, a three pole double throw switch 47' being interposed in these wires as shown. The variable potentiometer is controlled by a controller, generally designated at 55, which may be of any type responsive either directly or indirectly to the moisture content of the paper web 10 as it leaves the drier roll 14. For purposes of illustration, I have shown this controller 55 to be of the tension roll type. The slider 54 is carried by a pivoted lever 56 pivoted at 57. The lever 56 carries a roll 58 which engages the surface of the paper web 10 and this roll 58 is urged in a clockwise direction by means of an adjustable weight 59. As the moisture content of the paper web 10 increases, the paper web 10 expands and allows the weight 59 to move the slider 54 downwardly with respect to the potentiometer coil 52. This downward movement causes operation of the proportioning motor 47 to move the valve 46 towards an open position to increase the temperature of the air blast impinging the surface of the paper web 10 to increase the drying action thereof. As the moisture content of the paper web 10 decreases, the paper web 10 contracts to operate the slider 54 upwardly with respect to the potentiometer coil 52 against the action of the biasing weight 59. This upward movement of the slider 54 causes operation of the proportioning motor 47 to move the valve 46 towards a closed position to decrease the temperature of the air blast impinging the paper web 10 to decrease the drying action thereof.

From the above it will be seen that I have provided a control system wherein the majority of the 4 drying action is performed by the drier roll 14 and the drying action of this drier roll 14 is maintained substantially constant. Any variations in the moisture content of the paper web 10 leaving the drier roll 14 affects the moisture 4 responsive controller 55 to control the temperature of the air blast impinging the paper web 10 to increase or decrease the drying action thereof to maintain the moisture content of the paper web 10 leaving the drier roll 14 substantially constant at all times.

In order to control the drying action of the air blast by controlling the volume of air impinging the paper web 10 instead of by controlling the temperature of the air, the speed of the fan 5 may be varied or a volume damper may be provided between the fan 38 and the hood 37. For purposes of illustration, I have shown a volume damper 61 for this purpose. This volume damper 61 may be variably positioned by means of a proportioning motor 47' which is, in all respects, similar to the proportioning motor 47. Power 6 may be supplied to the proportioning motor 47' by means of line wires 48' and 49' leading from some source of power, not shown. Proportioning 6 motor 47' may be connected by wires 50', 51' and 52' to switch 47', which when moved to its downward position connects these wires to wires 50, 51 and 52 respectively and hence to the potentiometer of the moisture responsive controller 7 55. The arrangement is such that as the moisture content of the paper web 10 leaving the drier roll 14 increases, the volume damper 61 is operated to increase the flow of air and, likewise, if the moisture content of the paper web 10 de-

creases, the volume damper 81 is positioned to decrease the flow of drying air. From the foregoing, it should be apparent that the drying effect of the air may be controlled by varying either its temperature or quantity, and that either the temperature controller or the volume damper may be employed for controlling the drying effect by moving switch 41" to the desired position. If it be desirable to control both the volume of drying air and the temperature thereof, the proportioning motors 41 and 41' may both be used to accomplish this mode of operation. This may be done by bridging the opposite contacts of switch 41" or by omitting this switch entirely.

Referring now to Figures 2 and 3, I have shown my invention as applied to a Fourdrinier drier. The paper web leading from the forming end of a paper mill is generally designated at 65 and this paper web is passed over drying rolls 66 and a spring roll 67 to a calender stack 68. The paper web 65 is held against the upper drying roll 66 by means of a felt 69 suitably guided by guide rolls 70. The paper web 65 is also held against the lower drying roll 66 by a felt 71 suitably guided by means of guide rolls 72.

Heating fluid which may take the form of steam is supplied to a header 74 under the control of a valve 75 which may be positioned by a proportioning motor 76 which also may be of the type shown and described in the above referred to Cunningham patent. Power is supplied to this proportioning motor 76 by means of line wires 77 and 78 leading from some source of power, not shown. Steam is delivered from the header 74 by means of pipes 79 to each drier roll 66 to perform the drying action.

The proportioning motor 76 may be adjustably positioned by means of a controller, generally designated at 80, and which may comprise a bellows 81 for operating a slider 82 with respect to a potentiometer coil 83. The potentiometer coil 83 and slider 82 are connected to the proportioning motor 76 by wires 84, 85 and 86 respectively. If it be desired to operate the controller 80 in accordance with steam pressures in the header 74, the bellows 81 may be connected by a pipe 81 to the header 74. If it be desired to operate the controller 80 in accordance with the temperature of the drying rolls 66, the bellows 81 may be connected by a capillary tube to a bulb containing a volatile fill and located in any one of the drying rolls 66. The arrangement is such that as the steam pressure or temperature increases, the slider 82 is moved upward with respect to potentiometer coil 83 to operate proportioning motor 76 to position the valve 75 towards a closed position. Likewise, if the steam pressure or temperature decreases, the slider 82 is moved downward with respect to the potentiometer coil 83 to operate the proportioning motor 76 to position the valve 75 towards an open position. In this manner, the heat content, and consequently the drying action of the drying rolls 66, is maintained substantially constant at all times.

In a Fourdrinier drier, the paper web 65 and the felts 69 and 71 form pockets which intrap moisture laden air which retards materially the drying action on the paper web 65. It is, therefore, not only an object of this portion of the invention to complete the drying of the paper web 65 but also to rid these pockets of moisture laden air. In carrying this out, I provide air ducts 90 extending longitudinally of the Fourdrinier drier. The ducts 90 are provided with tuyères 91 for injecting heated air into and through the pockets,

this heated air causing a drying action on the paper web 65 and also ridding the pockets of moisture laden air. Heated air is delivered to the ducts 90 by means of branch ducts 92 emanating from a common duct 93 which receives heated air from a fan or blower 94, which may be driven in any suitable manner, such as by a pulley 95. Heated air is delivered to the fan or blower 94 through a duct 96 from a radiator or heat exchanger 97 which receives a supply of heating fluid such as steam from pipes 98. The volume of air delivered to the ducts 90, and consequently the drying action of the air blast, may be controlled by varying the speed of the fan 94, by a volume damper, or by means of a damper 99 which, for purposes of illustration, is shown to be a by-pass damper, the by-pass being afforded by a duct 100.

Referring specifically to Figure 3, with the by-pass damper 99 in the position shown, substantially all of the air delivered by the fan is being forced into the pockets of the drier. As the damper 99 is positioned towards the left, the supply of heated air to the pockets is decreased and the excess air is delivered into the by-pass duct 100.

The by-pass damper 99 may be adjustably positioned by a proportioning motor 101 which receives a supply of power from line wires 102 and 103 leading from some source of power, not shown. It may also be desired to control the drying action of the air blast not only by controlling the volume of air delivered, but also by controlling the temperature of this air. If this mode of operation be desired, the supply of steam to the heat exchanger or radiator 97 may be controlled by a valve 104 which may be adjustably positioned by a proportioning motor 105. Power is supplied to the proportioning motor 105 by means of line wires 106 and 107 leading from some source of power, not shown.

A moisture content responsive controller is generally designated at 108 for controlling the operation of the proportioning motors 101 and 105. This controller 108 may comprise a pivoted lever 109 carrying a tension roll 110 and an adjustable biasing weight 111. The lever 109 may operate sliders 112 and 113 with respect to potentiometer coils 114 and 115. The potentiometer coil 114 and its associated slider 112 may be connected by wires 117, 118 and 119 to the proportioning motor 105. In like manner, the potentiometer coil 115 and its associated slider 113 may be connected by wires 120, 121 and 122 to the proportioning motor 101.

As the moisture content of the paper web 65 leaving the Fourdrinier drier increases, the sliders 113 and 112 are moved downwardly with respect to their potentiometer coils 115 and 114 to operate the proportioning motors 101 and 105 to increase the volume of air being delivered to the pockets and also to increase the temperature thereof which increases the drying action of the air. As the moisture content of the paper web 65 decreases, the sliders 113 and 112 are moved upwardly with respect to the potentiometer coils 115 and 114 to operate the proportioning motors 101 and 105 to decrease the volume of air being delivered to the pockets and to decrease the temperature thereof whereby the drying action of the air blast is decreased.

If it be desired to control only the temperature of the air and not control the volume of the air, the damper 99 and the proportioning motor 101 may be omitted and, likewise, if it be desired to 75

control only the volume of the air and not the temperature thereof, the proportioning motor 188 may be omitted.

If it be desired to heat only that portion of the air which is delivered to the tuyères 81, a heat exchanger or radiator 128a may be placed in the duct 83 between the by-pass damper 88 and the branch ducts 82. Heating fluid in the form of steam may be supplied to this heat exchanger 128a by suitable pipes 121a and the supply of steam to the heat exchanger 128a may be controlled in exactly the same manner as the supply of steam to the heat exchanger 87 is controlled. This type of installation in some instances may be more economical since heated air is not bypassed by the by-pass damper 88.

From the above it is seen that in this modification, as in the previous modifications, I have provided a means whereby the drying action of the drying rolls is maintained substantially constant and that any variations in moisture content of the paper web leaving the drier are taken care of by means of the air blast, the drying effect of this air blast being controlled in accordance with the moisture content of the paper web. Therefore, an extremely simple and efficient control system is provided whereby the moisture content of the paper web leaving the driers is maintained substantially constant at all times. Also, it is seen that the majority of the drying action, which in this instance is accomplished by the steam drier rolls, is maintained constant and that variations in the moisture content of the paper web are taken care of by only adjusting a smaller portion of the drying action which, in this instance, is the air blast means. By reason of this mode of operation, an extremely sensitive control may be obtained. Further, in the modification of Figures 2 and 3, I have not only provided an accurate control system for controlling the moisture content of the paper web but have also provided a means for ridding the pockets of a Fourdrinier drier of moisture laden air whereby the drying action of the drier is extremely facilitated.

Although for purposes of illustration, I have shown various forms of my invention, other forms thereof may become obvious to those skilled in the art, and, consequently, my invention is to be limited only by the scope of the appended claims and prior art.

I claim as my invention:

1. In a drier of the class described for drying a substance, drying means for accomplishing a major portion of the drying action, control means responsive to the drying properties of said drying means for maintaining the drying action thereof substantially constant, other drying means for completing the drying action, and means responsive to the moisture condition of the substance to vary said other drying means to increase or decrease its drying action.

2. In a device of the class described for drying a substance, steam drying means for accomplishing a portion of the drying action, means responsive to a heating property of the steam for maintaining the drying action thereof substantially constant, air drying means for accomplishing the remainder of the drying action, and means responsive to the moisture in the substance for controlling said air drying means whereby the substance is dried to a predetermined degree regardless of its initial condition.

3. In a drier of the class described having drier roll means over which the substance to be dried

is fed for accomplishing the drying action, the combination of air blast means also for accomplishing a drying action, control means responsive to the drying properties of the drier roll means for maintaining the drying action thereof substantially constant, and other control means responsive to the moisture condition of the substance for varying the drying action of the air blast means, both of said control means coacting to accomplish a drying action for maintaining the final condition of the substance to be dried substantially constant regardless of its initial condition.

4. In a drier of the class described having steam drier roll means over which the substance to be dried is fed for accomplishing a drying action, the combination of control means responsive to a heating property of the heating medium supplying heat to the drier roll means for controlling the supply of steam thereto for maintaining the drying action thereof substantially constant, hot air blast means also for accomplishing a drying action and comprising ducts, fan means and heat exchanger means, and other control means responsive to the moisture content of the substance for controlling the drying action of said air blast means to maintain the final condition of the substance substantially constant.

5. In a drier of the class described having steam roll means over which the substance to be dried is fed for accomplishing a drying action, the combination of control means responsive to a heating property of the steam supplied to said steam roll means for controlling the supply of steam thereto for maintaining the drying action thereof substantially constant, hot air blast means also for accomplishing a drying action and comprising ducts, fan means and heat exchanger means, and other control means responsive to the moisture content of the substance for controlling the heat content of said heat exchanger means whereby the drying action of said hot air blast means is varied to maintain the final condition of the substance substantially constant.

6. In a drier of the class described having steam roll means over which the substance to be dried is fed for accomplishing a drying action, the combination of control means responsive to a heating property of the steam supplied to said steam roll means for controlling the supply of steam thereto for maintaining the drying action thereof substantially constant, hot air blast means also for accomplishing a drying action and comprising ducts, fan means, damper means and heat exchanger means, and other control means responsive to the moisture content of the substance for controlling the operation of said damper means whereby the drying action of said hot air blast means is varied to maintain the final condition of the substance substantially constant.

7. In a drier for removing moisture from a substance, in combination, air blast means for causing a flow of air across the substance being dried to accomplish a drying action, a controller for varying the drying action of said air blast drying means, motor means for positioning said controller, a device responsive to the moisture content of the substance being dried, and means actuated by said device for controlling said motor means in a manner to increase the drying action of said air blast drying means upon an increase in moisture content of the substance being dried, and to decrease the drying action upon a decrease in moisture content.

8. In a drier for removing moisture from a sub-

stance, in combination, air blast means for causing a flow of air across the substance being dried to accomplish a drying action, a controller for varying the rate of air flow across the substance being dried to thereby vary the drying action of the air blast drying means, motor means for positioning said controller, a device responsive to the moisture content of the substance being dried, and means actuated by said device for controlling said motor means in a manner to increase the rate of air flow over the substance being dried upon an increase in moisture content of the substance being dried, and to decrease the rate of air flow upon a decrease in moisture content.

5. In a drier for removing moisture from a substance, in combination, air blast means for causing a flow of air across the substance being dried to accomplish a drying action, means including a controller for varying the temperature of said air blast for thereby varying the drying action of said air blast drying means, motor means for positioning said controller, a device responsive to the moisture content of the substance being dried, and means actuated by said device for controlling said motor means in a manner to increase the temperature of said air blast

10. In a drier of the class described having steam roll means over which the substance to be dried is fed for accomplishing a drying action, the combination of motor means for controlling the supply of steam to said steam roll means, a variable resistance operatively related to said motor means, means responsive to variations in a heating property of said steam roll means for varying said resistance to control said motor means proportionately to maintain the heat content of said steam roll means constant, air blast means also for accomplishing a drying action, motor means for controlling said air blast means, a variable resistance operatively associated therewith, and detector means responsive to variations in the moisture condition of the substance for varying said resistance to control said motor means proportionately whereby the drying action of said air blast means is varied to maintain the final condition of said substance substantially constant.

15. In a drier for removing moisture from a substance, in combination, air blast means for causing a flow of air across the substance being dried to accomplish a drying action, motor means for controlling said air blast means, a variable resistance operatively associated therewith, and detector means responsive to variations in the moisture condition of the substance for varying said resistance to control said motor means proportionately whereby the drying action of said air blast means is varied to maintain the final condition of said substance substantially constant.

20. In a drier for removing moisture from a substance, in combination, air blast means for causing a flow of air across the substance being dried to accomplish a drying action, motor means for controlling said air blast means, a variable resistance operatively associated therewith, and detector means responsive to variations in the moisture condition of the substance for varying said resistance to control said motor means proportionately whereby the drying action of said air blast means is varied to maintain the final condition of said substance substantially constant.

25. In a drier for removing moisture from a substance, in combination, air blast means for causing a flow of air across the substance being dried to accomplish a drying action, motor means for controlling said air blast means, a variable resistance operatively associated therewith, and detector means responsive to variations in the moisture condition of the substance for varying said resistance to control said motor means proportionately whereby the drying action of said air blast means is varied to maintain the final condition of said substance substantially constant.

RUTCHER SKAGERBERG.
